UNITED STATES PATENT OFFICE.

SAMUEL S. BEHREND, OF CHICAGO, ILLINOIS.

STARCHING-MACHINE.

SPECIFICATION forming part of Letters Patent No. 699,942, dated May 13, 1902.

Application filed March 28, 1900. Serial No. 10,572. (No model.)

To all whom it may concern:

Be it known that I, SAMUEL S. BEHREND, a citizen of the United States, residing at Chicago, in the county of Cook and State of Illinois, have invented certain new and useful Improvements in Starching-Machines, of which the following is a specification.

The object of this invention is to produce a machine for starching small articles of wearing-apparel, such as collars and cuffs, without stretching, wrinkling, or unduly wearing them.

In the accompanying drawings, Figure 1 is a side elevation of my improved starching-machine. Fig. 2 is a longitudinal section through said starching-machine on dotted line 2 2, Fig. 3. Fig. 3 is a transverse vertical section on dotted line 3 3, Fig. 2. Fig. 4 is a fragmental sectional view through the outer end of one of the starching-wheels, showing the vertically-movable journal-bearing for said wheel. Fig. 5 is a fragmental view showing the means for yieldingly supporting the starching-rollers in the cradles. Fig. 6 is a fragmental sectional view showing the two starching-belts with an article to be starched lying between them.

In the construction of this starcher I provide a supporting-framework A, in the upper part of which is secured a starch-receptacle A', supported in the framework in any suitable manner, as by bolts (not shown) passing through the openings A² in the sides of the framework A. This starch-receptacle is made, preferably, of sheet metal and is adapted to contain starch in a liquid form, and to keep the liquid starch at a certain temperature steam-coils A³ are provided underneath the receptacle A'. In the bottom of the starch-receptacle I provide a valve A⁴, by means of which the liquid contents of the receptacle may be drawn off. A feeding-table A⁵ is provided at the forward end of the machine and a receiving-table A⁶ at the rear end of the machine, the feeding-table being adapted to support articles intended to be passed through the machine and the latter to receive them after they have been starched by the mechanism.

A framework B lies within the starch-receptacle A', said framework being pivotally mounted at one of its ends upon the studs B',

secured to the side walls of the starch-receptacle. The opposite end of the framework B is supported within said receptacle upon similar studs B², likewise secured to the side walls of the starch-receptacle. The framework B is composed of two side members B³ and B⁴, united by means of the bolts B⁵. Each of the side members B³ and B⁴ is composed of three loops of U form adapted to support the journal-bearing blocks B⁶, within which blocks the starching-rollers B⁷ are rotatably mounted. Each of the journal-bearing blocks B⁶ is slidably held within a groove B⁸, formed in the concave edges of said side members B³ and B⁴, and is held outward therein by the coil-spring B⁹, lying between the end of the groove B⁸ and the journal-bearing block. The starching-rollers B⁷, rotatably mounted within the side members of the frame B, constitute three semicircular starching-cradles, the one adjacent to the pivotal support of the framework B being indicated upon the drawings by the numeral 1, the second or middle starching-cradle by the numeral 2, and the third or outside starching-cradle by the numeral 3. Articles to be starched pass in the operation of the mechanism through the starching-cradles in the order mentioned. Rollers B¹⁰, B¹¹, and B¹², covered with felt or other soft material, are rotatably mounted in bearings B¹³ in the upper extremities of the side members B³ and B⁴ of the framework B. The journal-bearings of each of these rollers are made vertically yielding within the elongated openings B¹⁴, being depressed within said openings by means of the coil-springs B¹⁵.

A starching-wheel C is mounted upon the rotatable shaft C' concentric with the curve of cradle No. 1. The wheel C comprises two spiders C², fixed to the shaft C' at opposite sides of the starch-receptacle A'. These spiders have peripheral rims C³, within which are journaled the shafts C⁴ of the starching-rollers C⁵, rotatably mounted between said peripheral rims. Outside of the supporting-framework A the shaft C' carries the worm-wheel C⁶, fixed to said shaft, by means of which wheel said shaft is rotated within the journal-bearing blocks C⁷. The journal-bearing blocks C⁷ are provided with flanges to bear against the inner side of the starch-receptacle A', and thus to hold said bearing-blocks

in position. In the circular cradle No. 2 a similar starching-wheel D is supported upon the rotatable shaft D'. This starching-wheel has the spiders D² with the circular rims D³, 5 and instead of the starching-rollers C⁵, rotatably mounted between said rims, as in the wheel C, the wheel D is provided with rubbing-blocks D⁴, fixed between said rims D³. These blocks are provided with concave faces 10 adapted to engage and rub over the faces of the starching-rollers B⁷ of cradle No. 2. The shaft D' is rotated by the worm-wheel D⁵, fixed to the outer end of said shaft, and is supported within the bearing-blocks D⁶, identical in form with the bearing-blocks C⁷ of the wheel C. In cradle No. 3 a starching-wheel E, identical in construction with the starching-wheel C, is mounted upon the shaft E'. The starching-wheel E has the spiders 15 E² and the peripheral rims E³, within which are journaled the shafts E⁴ of the starching-rollers E⁵. It also has a worm-wheel E⁶, fixed to the outer end of said shaft E', and journal-bearing blocks E⁷, similar to the journal-bearing blocks C⁷, hereinbefore described.

An endless apron F, of canvas or other closely-woven fabric, is placed around the starching-rollers B⁷, and a similar endless apron G, but of a fabric of a more open texture, is mounted upon and extends around the starching-wheel C and the roller B¹², also passing beneath and over the starching-wheels D and E. Both of the endless starching-aprons thus pass between the starching-rollers B⁷ of cradle No. 1 and the starching-rollers C⁵ of the starching-wheel C between the starching-rollers B⁷ of cradle No. 2 and the concave rubbing-blocks D⁴ of the starching-wheel D; also, between the starching-rollers B⁷ of cradle No. 3 and the starching-rollers E⁵ of the starching-wheel E.

H is a drive-shaft rotatably mounted upon the side of the supporting-framework A by means of the journal-bearings H'. This drive-shaft H is provided with three worms H², H³, and H⁴, meshing with the worm-wheels C⁶, D⁶, and E⁶, respectively. At the forward end of the machine the shaft H is provided with a tight and a loose pulley H⁵ and H⁶, respectively, for receiving a drive-belt, (not shown,) and a belt-shifter H⁷, mounted upon the side of the supporting-framework A, is adapted to shift said belt from the loose to the tight pulley, or vice versa, accordingly as it is desired 55 to start or stop the mechanism.

In the operation of this starcher liquid starch is placed within the receptacle A' and power applied to rotate the starching-wheels C, D, and E. Articles to be starched are fed 60 into the machine at the forward end between the aprons F and G. The movement of these aprons carries the article through cradle No. 1, between the starching-rollers B⁷ and the concave rubbing-blocks D⁴ in cradle No. 2, 65 and between the starching-rollers B⁷ and the starching-wheel E in cradle No. 3, discharging the starched article upon the receiving-

table A⁶ at the rear of the machine. Between cradles 1 and 2 and 2 and 3 the aprons run between the upper starching-rollers B⁷ and 70 the padded rollers B¹⁰ and B¹¹, forcing the starch through and into the fabric of the article passing through the machine. The starching-rollers B⁷ and the covered rollers B¹⁰, B¹¹, and B¹² are made bodily yielding by 75 means of their backing-springs B⁹ and B¹⁵, respectively. The concave rubbing-blocks D⁴ provide a larger surface of contact than the rollers C⁵ and E⁵ of the starching-wheels C and E, and therefore force the starch more 80 thoroughly through the fabric of the article being carried through the machine.

Various slight changes might be made in the general form and arrangement of the several parts hereinbefore described without departing from the spirit and scope of my invention, and for this reason I desire to have it understood that I do not hereby limit myself to the construction set forth.

I claim as my invention—

1. In a starching-machine, in combination, 90 a supporting-frame; a starch-receptacle; a starching-cradle comprising a series of starching-rollers; a starching-wheel adapted to rotate in said starching-cradle; said wheel carrying a series of starching-rollers; an endless apron adapted to travel with the starching-rollers in said cradle; an endless apron adapted to travel with the starching-rollers on said starching-wheel to move said aprons at the 95 same rate of speed with relation to each other; and means for rotating said wheel.

2. In a starching-machine, in combination, 100 a supporting-frame; a starch-receptacle; two starching-cradles each comprising a series of starching-rollers; a starching-wheel for each of said starching-cradles, one of said wheels carrying a series of starching-rollers, the other wheel being provided with a series of rubbing-blocks; an endless apron adapted to 105 travel with the starching-rollers; an endless apron adapted to travel with the starching-wheels; and means for rotating said wheels.

3. In a starching-machine, in combination, 110 a supporting-frame; a starch-receptacle; three starching-cradles, each comprising a series of starching-rollers; a starching-wheel for each of said starching-cradles, two of said wheels carrying a series of starching-rollers, the other one of said wheels being provided 115 with a series of rubbing-blocks; an endless apron adapted to travel with the starching-rollers in said cradles; an endless apron adapted to travel with the starching-wheels; and means for rotating said wheels.

4. In a starching-machine, in combination, 120 a supporting-frame; a starch-receptacle; a substantially semicircular starching-cradle pivotally supported within said receptacle; a starching-wheel rotatably mounted concentrically with the arc of the circle described by said cradle; a peripheral series of starching-rollers on said wheel; a series of starching-rollers rotatably mounted in yielding bear- 125 130

- ings in said cradle and adapted to be held in contact with the starching-rollers on said wheel; an endless apron adapted to travel with the starching-rollers in said cradle; an 5 endless apron adapted to travel with the starching-rollers on said starching-wheel; and means for rotating said wheel to move said aprons at the same rate of speed with relation to each other.
- 10 5. In a starching-machine, in combination, a supporting-frame; a starch-receptacle; a framework pivotally mounted within said starch-receptacle, said framework comprising two starching-cradles; a series of starching- 15 rollers yieldingly mounted within said framework, for each of said cradles; a rotatable starching-wheel concentric with the arc of the circle described by one of said cradles; a starching-wheel concentric with the arc of the 20 circle described by the other of said cradles, said last-mentioned starching-wheel being provided with a series of peripheral rubbing-blocks; a yieldingly-mounted roller having an elastic face intermediate said starching- 25 wheels; an endless apron adapted to travel with the starching-rollers of said cradles; an endless apron adapted to travel with the starching-wheels; and means for rotating said wheels.
- 30 6. In a starching-machine, in combination, a supporting-frame; a starch-receptacle; a framework pivotally mounted within said receptacle, said framework comprising three starching-cradles, each provided with a series 35 of starching-rollers rotatably mounted in yielding bearings, the rollers of each cradle

being disposed on the arc of a circle; three starching-wheels rotatably mounted in bearings in the supporting-frame, each of which starching-wheels is concentric with the arc 40 of the circle described by said starching-rollers, two of said wheels also being provided with a peripheral series of starching-rollers, the intermediate wheel having a peripheral series of rubbing-blocks; three rotatable rollers 45 yieldingly supported in said frame and being provided with elastic faces; an endless apron adapted to surround and travel with the starching-rollers of said cradles; an endless apron adapted to surround and travel 50 with the three starching-wheels and the three rollers with elastic faces; and means for rotating the starching-wheels.

7. In a starching-machine, in combination, a supporting-frame; a starch-receptacle; a 55 substantially semicircular starching-cradle pivotally mounted within said receptacle, said cradle comprising a series of starching-rollers; a starching-wheel adapted to rotate in said starching-cradle, said wheel carrying 60 a peripheral series of rubbing-blocks; an endless apron adapted to travel with the starching-rollers in said cradle; an endless apron adapted to travel with said starching-wheel; and means for rotating said wheel. 65

In testimony whereof I affix my signature in presence of two witnesses.

SAMUEL S. BEHREND.
